UNITED STATES PATENT OFFICE

108,645

DESIGN FOR A TOY TELEPHONE

John B. Jewett, Jr., Newtown, Ohio, assignor to Skymasters Corporation, Cincinnati, Ohio, a corporation of Ohio

Application October 18, 1937, Serial No. 72,248

Term of patent 3½ years

To all whom it may concern:

Be it known that I, John B. Jewett, Jr., a citizen of the United States, residing at Newtown, in the county of Hamilton and State of Ohio, have invented a new, original, and ornamental Design for a Toy Telephone, of which the following is a specification, reference being had to the accompanying drawing, showing the face side thereof, the opposite side of the same being plain and unornamented.

Figure 1.

I claim:

The ornamental design for a toy telephone substantially as shown and described.

JOHN B. JEWETT, JR.
